UNITED STATES PATENT OFFICE.

JAMES L. GARVER, OF BUFFALO, NEW YORK.

RESILIENT WHEEL.

1,367,596.

Specification of Letters Patent.

Patented Feb. 8, 1921.

Application filed April 21, 1917. Serial No. 163,734.

To all whom it may concern:

Be it known that I, JAMES L. GARVER, a citizen of the United States, residing at Buffalo, in the county of Erie and State of New York, have invented new and useful Improvements in Resilient Wheels, of which the following is a specification.

This invention relates to a resilient wheel and has for its objects the production of a wheel of this character in which the driving effort is cushioned in both directions, in which the bearing points between the members on the hub and rim are staggered so that they are in different planes and increase the stability of the wheel, in which a plurality of rows of springs are employed so as to increase the resilient capacity of the wheel, in which the rebound is effectively checked, and in which the bearing surfaces between the relatively movable contact surfaces of the parts on the hub and rim are constructed to provide ample wear and greater durability, and in which these objects are attained by means which are comparatively simple in construction, easy to manufacture and not liable to get out of order.

In the accompanying drawings:

Figure 1 is a section of a wheel in a plane at right angles to its axis showing one embodiment of my improvements, the section being taken on line 1—1, Fig. 3, looking rearwardly or toward the vehicle. Fig. 2 is a similar section taken on line 2—2, Fig. 3. Figs. 3, 4 and 5 are transverse sections of the wheel taken on the correspondingly numbered lines in Fig. 2. Figs. 6, 7 and 8 are fragmentary circumferential sections taken on the corresponding numbered lines in Fig. 1. Fig. 9 is a section taken on line 1—1, Fig. 3, looking forwardly or away from the vehicle. Fig. 10 is a detached front view of a part of the rebound checking device associated with my resilient wheel.

Like characters of reference indicate corresponding parts throughout the several views.

My improvements may be organized so as to produce a wheel which merely supports the load on the wheel resiliently, as would be the case in the steering wheels of an automobile or other vehicle, but the same may

also be organized so as to yieldingly take the torque or driving effort which is transmitted from an engine to a traction wheel, as would be the case in the driving wheels of an automobile as now commonly constructed. In the drawings, provision is made for cushioning both the radial displacement of the axle or hub relatively to the rim of the wheel due to the load which may be imposed upon the wheel, and also the circumferential displacement of the hub or axle and the rim of the wheel in either direction relatively to one another due to the driving effort of the motor which is transmitted from the hub to the rim, but it is to be understood that my improvements comprehend these features regardless of whether they are embodied individually in different wheels or collectively in the same wheel.

1 represents an axle, 2 a tubular hub mounted on this axle and 3 a wheel rim surrounding the axle. In the case of a steering wheel, the hub may be journaled on the axle which is usually stationary, but when the axle is turned by power, the hub is secured to the axle so as to rotate therewith. The construction shown in the drawings represents the hub secured to the axle so that the same may be utilized for transmitting a tractive effort to the wheel, this connection between the hub and axle being effected in any suitable manner, for instance, by means of a key 4 arranged between these parts, as shown in Figs. 1, 2 and 3. The rearward movement of this hub on the axle is preferably limited by engaging the rear end of the hub with a collar or shoulder 5 arranged on the axle, as shown in Figs. 3, 4 and 5.

If desired, the periphery or outer face of the wheel rim may be provided with a tire of any suitable construction but in the drawings the same is shown plain. If desired, my improvements may be embodied in a wheel having a hub surrounded by spokes and a tire, for instance the rim 3 may be regarded as a supplemental hub and connected by spokes with another outer rim or tire surrounding the rim 3.

The resilient means which are interposed between the hub and rim of the wheel and which embody my invention are preferably constructed as follows:

7 represents a plurality of front abut-

ments which are arranged in an annular row on the front part of the bore of the wheel rim, 8 a plurality of rear abutments arranged in an annular row on the rear part 5 of the bore of the wheel rim, and 9 a plurality of intermediate abutments arranged in an annular row on the central part of the bore of the wheel rim between the front and rear sets of abutments. Each of the 10 intermediate abutments preferably tapers inwardly and has its opposite sides relatively to the circumference of the wheel preferably provided with curved bearings 10, 10^a, as shown in Figs. 1 and 2. These 15 curves should preferably be the arc of a circle whose radius is approximately equal to the distance of the possible relative radial movement of the inner and outer wheel members plus the distance on the shoe 24 20 from its pivotal point to its arc of bearing, and described from a point approximately on the circumference of the circle passing through the pivotal points of the shoes.

Each of the front abutments is provided 25 with a curved bearing 11 which faces circumferentially in one direction and each of the rear abutments is provided with a curved bearing 12 which faces circumferentially in the opposite direction.

30 13 represents a rear driving spider or disk arranged at right angles to the axis of the wheel within the rear part of the wheel rim and secured with its inner part to the hub by means of rivets 14 passing through this 35 disk and an annular flange 15 on the hub so as to be compelled to turn with the hub and axle, although, if desired, this connection may be effected in any other suitable manner. This rear disk has its peripheral portion, preferably, though not necessarily, arranged to the rear of the rear abutments of the rim, as shown in Figs. 3, 4 and 5.

16 represents an intermediate cushion disk or spider arranged in front of the rear disk 45 and rotatable circumferentially relatively to the axle and hub, this being accomplished for instance, as shown in Figs. 1-5, by providing the central part of this intermediate disk with a forwardly projecting 50 bearing sleeve 17 which is journaled on the central part of the hub and confined against axial movement thereon by engaging the rear end of this bearing sleeve with the front end of a collar 18 on the rear disk 55 while the front end of this bearing sleeve engages with a screw nut 19 engaging with the externally screw threaded front end of the hub, as shown in Figs. 3, 4 and 5. The intermediate disk is preferably arranged in 60 a plane between the rear and intermediate sets of abutments.

20 represents a front cushion disk or spider which is arranged within the front part of the rim and capable of turning circumferentially relatively to the hub, rim, 65

and the rear and intermediate disks, this being preferably accomplished by providing the central part of this front disk with a rearwardly projecting bearing sleeve 21 which is journaled on the periphery of the 70 bearing sleeve of the intermediate disk, as shown in Figs. 1-5. This front disk is preferably arranged in a plane between the front and intermediate sets of abutments, 75 as shown in Figs. 3-5.

On its marginal part, the front bearing disk is provided with a set of front bearing shoes 22 which engage with the corresponding curved bearings 11 of the front set of abutments and on the rear side of its marginal part this front disk is provided with an annular row of bearing shoes 23 which engage with those bearings 10 of the intermediate set of abutments which face circumferentially in the same direction as the 80 bearings of the front set of abutments which are engaged by the front shoes 22.

The marginal part of the intermediate disk is provided with a plurality of front bearing shoes 24 which engage with the 90 bearings 10^a of the intermediate abutments which are circumferentially opposite to the bearings 10 and the intermediate disk is also provided on its marginal part with an annular row of rear bearing shoes 25 which engage with the curved bearings 12 of the 95 rear set of abutments which face circumferentially in the same direction as the bearings 10^a.

The front and rear bearing shoes of the 100 front disk preferably alternate with each other so that they are staggered in a direction circumferentially of this disk and the front and rear bearing shoes of the intermediate disk are alternated and staggered 105 circumferentially in like manner, as shown in Fig. 8. Each of these shoes may be of any approved construction so as to slidingly engage its companion bearing on the respective abutment, this being accomplished for 110 instance by pivotally mounting each of these shoes by means of a bolt 26 on the margin of its respective disk and providing the same with a curved bearing face 27, whereby the same may slide on the cooperating bearing 115 face of the respective abutment, as shown in the drawings, thereby providing a large contact area between each shoe and its abutment and reducing the wear upon the same accordingly.

120 Adjacent to its margin the front spider or disk is provided with a plurality of segmental openings 28 which are arranged in an annular row around the axis of the wheel, one end of each of these openings being provided with a spring seat or lug 29 which faces circumferentially in one direction and a stop 30 at its opposite end which faces circumferentially in the opposite direction and is preferably provided with an 125 130

elastic facing 30^a. On its front side the intermediate disk is provided with a plurality of intermediate cushion lugs or seats 31 which are arranged in an annular row and 5 each of which projects forwardly into one of the segmental openings 28 of the front disk and is adapted to normally engage with the stop at one end of this opening, as shown in Fig. 1. The intermediate disk is 10 also provided with an annular row of segmental openings 32 which are preferably arranged circumferentially in line with the cushion lugs 31 thereof.

On its front side the rear disk is provided 15 with an annular row of rear driving lugs or seats 33 each of which projects forwardly through a companion pair of segmental openings 32, 28, in the intermediate and front disks between the spring seat 29 at one 20 end of the respective opening in the front disk and the cushion lug 31 of the intermediate disk arranged in the opposite end of the respective slot of the front disk.

34 represents a plurality of springs arranged in an annular row around the axle 25 of the wheel and each bearing at one end against the spring seat 29 at one end of one of the openings 28 in the front disk while the opposite end of this spring bears against 30 one side of the driving lug 33 of the rear disk. 35 represents an annular row of springs arranged around the axis of the wheel and each bearing at one end against 35 the cushion lug 31 of the intermediate disk in one opening 28 of the front disk while its opposite end bears against the opposite side of the driving lug 33 of the rear disk arranged in the same opening of the front disk. Each pair of springs 34 and 35 constitute a unit. The springs 34 and 35 are 40 preferably arranged in the same circumferential line but alternate with each other, as shown in Figs. 1 and 2. It is obvious that the springs may be caged and that springs 45 of varying sizes of material and of varying lengths may be used by which means the resilient action of the wheel may be widely modified.

Assume that the wheel is at rest and that 50 a load is imposed upon the hub which will cause the latter to move radially downward in a substantially vertical line toward the lowermost part of the rim. In this case, the front disk will slidably fulcrum by means 55 of that one or more of its bearing shoes on the companion abutments which are farthest to the left in Fig. 1 and cause this disk to turn about the hub in the direction of the arrow 36 in this figure, and at the same 60 time, the intermediate disk will slidably fulcrum by means of that one or more of its bearing shoes on the companion abutments which are farthest to the right in Fig. 2, and cause the intermediate disk to turn on 65 the hub in the direction of the arrow 37 in

Fig. 2. Under such assumption the driving lugs 33 of the rear disk would be relatively stationary and in this case all the spring seats 29 of the front disk would move toward one side of the rear driving lugs 33 to 70 an equal extent and cause all of the springs 34 to be flexed uniformly, and at the same time all of the cushion lugs 31 of the intermediate disk would move simultaneously 75 an equal extent toward the opposite sides of the rear driving lugs 33 and uniformly flex the several springs 35, so that the combined flexing effect which at this time is exerted upon the springs 34, 35, serves to resist the downward radial displacement of the hub 80 toward the lower part of the wheel rim and to cushion the weight of the load imposed upon the wheel accordingly. When the hub is displaced upwardly relatively to the rim, the fulcrums of the front and intermediate 85 cushion disks are reversed or shifted from one side of the axis of the wheel to the other relatively to each of these disks, but the operation is the same. When one or more of the bearing shoes of a cushion disk 90 operates as a sliding fulcrum on one of the abutments of the rim, all the other shoes of the same disk move away from their companion abutments more or less, depending on the distance of the same from the location of the shoe which for the time being 95 serves as the fulcrum.

Assuming that only an effort is imparted to the hub which would tend to turn the same circumferentially relatively to the rim, 100 then the rotary movement of the rear driving lugs 33 of the rear disk upon turning in the direction of the arrow 36, would cause the set of springs 35 to be flexed and the other set of springs 34 to be relieved, 105 while upon moving these rear driving lugs circumferentially in the opposite direction, the several springs 34 would be flexed and the springs 35 of the other set would be relieved, but in either case the driving torque 110 would be yieldingly transmitted from the hub to the rim either by the springs 35 or other springs 34, and thereby cushion this driving effort and relieve the transmission line from injurious strains. Assuming, however, that 115 there is a load sufficient to start the axle from center; then the springs 34 or 35 on the opposite side of the lugs 33 from those springs 34 or 35 which resist the torque, are not relieved by the torque but continue to 120 carry the load, moving *en masse* to whatever extent the torque flexes the opposite springs. These effects are modified more or less by the springs 42, later explained, according to the strength of the springs 42 relative to the 125 springs 34, 35.

When the wheel is subjected to both load strains which displace the hub and rim radially relatively to each other, and to driving strains which operate to shift the 130

hub and rim circumferentially relatively to each other, then a resultant effect is produced upon the springs 34 or, according to the direction of the torque, 35, due to the combination of these movements both of which would be yieldingly resisted by these springs in proportion to the load and driving effort and thereby cushion its effect upon the wheel accordingly.

10 In order to further cushion the wheel against strains due to radial displacement of the hub and rim relatively to each other, a modified form of the cushioning means just described is employed in addition thereto. As shown in Figs. 1-5 and 7, this supplementary cushioning means comprises a plurality of segmental openings 38 in the intermediate and front disks 16 and 20 which are arranged in an annular row around the 20 axis of the wheel, each having a spring seat 39 at one of its ends and a stop 40 at its opposite end preferably provided with an elastic facing 40^a, a plurality of cushion lugs 41 arranged on the front side of the 25 intermediate disk and each projecting forwardly through one of the segmental openings 38 and normally engaging with the stop 40 at one end thereof, and a plurality of cushioning springs 42 arranged in an 30 annular row around the axis of the wheel and each arranged in one of the segmental openings 38 and bearing at one end against the spring seat at one end thereof while its opposite end bears against the cushion lug 35 therein.

Upon radially displacing the hub and rim of the wheel relatively to each other and causing a rotary movement of the front disk about the axis of the wheel in one direction 40 and a rotary movement of the intermediate disk about the axis of the wheel in the opposite, as has been previously described, each of the spring seats 39 of the front disk and the companion cushion lug 41 approach 45 each other an equal extent and thereby cause each spring 42 to be flexed more or less in accordance with the extent of the radial movement of the hub and rim relatively to each other, but all of the inner springs 42 will be flexed uniformly and to the same 50 extent, regardless of the direction of the radial movement of the hub and rim relatively to each other. It will be noted that the action upon these inner springs 42, as 55 just described, is the same as the action upon the springs 34, 35, when no driving strains are transmitted from the hub to the rim in the direction circumferentially of the wheel, whereby the spring elements in all 60 parts of the wheel are flexed uniformly and at the same time under these circumstances. By modification of the springs 42 relative to the springs 34, 35, the cushioning of the torque is modified as will be readily seen.

65 By providing two sets of bearings on the

rim and two sets of shoes on each cushion spider for engagement therewith and staggering said bearings and shoes, a greater number of contact points between each of these spiders and the rim is obtained so 70 as to render the cushioning effect uniform in all positions of the hub and rim, and also lessen the distance of travel of each shoe upon its bearing when the wheel is turning in eccentric position, thus lessening frictional contact of parts. 75

In order to exclude dirt, dust and water from the internal parts of the resilient wheel, a rear cover 43 is applied to the rear side thereof, the same being preferably secured at its margin by means of bolts 44 or the like on the rim of the wheel while its central part bears against the rear side of the driving disk 13 to guide the wheel and is provided with an opening 45 through 80 which the axle projects, and a front cover 46 is provided which extends across the front end of the axle and associated parts and is secured at its margin to the wheel rim by means of bolts or screws 47 entering the 85 front abutments. 90

In order to prevent noise from the sudden contact between the bearing surfaces upon rebounding of the hub and rim into their normal central position after these parts 95 have been displaced or shifted into an eccentric position relatively to each other, a rebound checking device is provided which is preferably constructed as follows, and best shown in Figs. 3, 4, 5, 9 and 10: 100

48 represents a double wedge or spreading device which is arranged on one side of the axis of the wheel and provided on its opposite sides with salient points 49 which are arranged about midway of the length of the spreader, two inner inclined or cam faces 50 which converge inwardly from said salient points and form an inner wedge and two outer inclined or cam faces 51 which converge outwardly from said salient points 110 and form the outer wedge of the spreader. 52, 52 represent two thrust members forming part of a retarding device and provided with bearing shoes 53, 53 engaging with opposite sides of the spreader and yieldingly held in engagement therewith by spring means. The spreading device and the retarding device are so mounted that one of these elements moves with the rim and the other with the hub and axle relatively to the 115 axis of the wheel but in the construction shown in the drawings which is an example of one embodiment of this feature, the retarding device is mounted to move bodily with the axle and hub but capable of turning about the axis of these parts, and the spreading device is mounted to move bodily with the rim but capable of turning relatively thereto about the axis thereof. For this purpose the spreader is preferably ar- 120 125 130

ranged on the rear or inner side of the front cover 46 and above the axis of the rim and provided at its lower end with a pivot ring 54 which turns on a pivot boss or stud 55 arranged 5 on the inner side of the front cover. This pivot ring is retained in place on this stud by means of a retaining plate 56 engaging with the rear side of the spreader and secured to the stud by means of a screw 57, 10 as shown in Figs. 3 and 4. The spreader is normally held above the axis of the rim by means of a pendent weight 58 formed on or secured to the spreader and arranged below the pivot stud, this weight being 15 heavier than the spreader so that the latter will normally point upwardly regardless of the rotation of the rim upon which the same is mounted.

The thrust members 52, 52 are preferably 20 constructed in the form of levers which are arranged on opposite sides of the axis of the hub and axle and have their opposing central parts pivotally mounted on the front end of the axle between a shoulder 59 on the 25 latter and a screw nut 60 applied to the front end of the same. The upper arms 61 of the levers are comparatively light and carry the bearing shoes 53, 53, and between the lower arms of the same which are comparatively 30 heavy, a tension device is arranged which constantly tends to spread these lower arms and hold the shoes on the upper arms thereof yieldingly in engagement with opposite sides of the spreading member. By thus 35 weighting the spreader and retarding arms, the same tend constantly to hang in a vertical position regardless of the circumferential position of the hub and rim. In its preferred form this tension device prefer- 40 ably comprises a dash pot which has its cylinder 62 formed integrally on the lower arm of one of the retarding levers concentrically with the axis thereof, a dash piston 63 arranged in the dash cylinder and prefer- 45 ably formed integrally with the lower arm of the other spreading lever, and a spring 64 surrounding the dash cylinder and piston and bearing at its opposite ends against the inner sides of the lower arms of the retard- 50 ing levers, as best shown in Figs. 9 and 10.

In the normal position of the axle and hub and the rim in which these parts are concentric the bearing shoes 53 of the shock absorber or checking device engage with the 55 high or salient points between the inner and outer wedges of the spreader, as shown in Figs. 3, 4, 9 and 10. Assuming that the axle and hub move below the normal position relatively to the axis of the wheel rim, 60 This will permit the shoes 53 of the retarding levers to approach each other as they slide downwardly in engagement with the inwardly and downwardly converging or tapering surfaces 50 of the lower wedge, 65 thereby permitting the spring 64 to expand,

and when the axle and hub again rise to their normal central position so that the bearing shoes are again spread to their maximum extent upon reaching the salient points 49, the spring 64 is again compressed 70 and thereby operates to retard the movement of the wheel from its eccentric to its concentric position. If the spreading and retarding devices become inverted as a result of swinging too far or due to frictional 75 tendency in the bearings by which they are carried then the shoes 53 of the retarding levers approach each other by reason of the sliding engagement of the same with the outwardly tapering or converging surfaces 80 51 of the upper or outer wedge at this time, it being understood that the tension of the spring 64 operates to spread the lower arms of the retarding levers and hold the bearing 85 shoes firmly in engagement with the inclined surfaces of the upper wedge. As the axle and hub again resume their normal position, the outer wedge spreads the two bearing shoes and compresses the spring 64 between the retarding levers until the bearing 90 shoes reach the salient points of the spreader, thereby serving to cushion the rebound of the hub and rim relatively to each other when these parts resume their normal position. If a shock occurs while the parts 48 95 and 53 are in a horizontal position then one of the parts 53 will engage with one of the inclined surfaces 50 and the other part 53 will engage with the diagonally opposite inclined surface 51 and then permit both the 100 parts 53 to first approach each other and then be forced apart again to produce the desired checking effect. The cup-shaped packing 65 arranged on the piston and engaging with the cylinder of the dash pot, 105 serves to trap the air in the cylinder and prevent its ready escape when the piston moves into the cylinder, thereby aiding the spring 64 in resisting the spreading action of the wedge on the shoes 53 of the retard- 110 ing levers and insuring a greater cushioning effect, but the withdrawal of the piston from the cylinder can be effected more easily by reason of the cup-shaped packing, thereby enabling this spring 64 to 115 promptly spread the lower arms of the retarding levers and enable the bearing shoes on the upper arms thereof to properly follow the respective wedge from the wide to the narrow part thereof.

In the operation of this wheel, the retarding devices of this noise preventing mechanism may, if the wheel members are concentric, rotate with the wheel; but this rotation will be promptly stopped when the parts 49 125 and 53 are no longer in a common circumference; but regardless of the position of these parts at the instance of radial displacement they will fulfil their purpose of retarding the return of axle to the center. 130

I claim as my invention:

*1. A resilient wheel comprising a hub, a rim, and cushioning means interposed between said hub and rim and comprising two members rotatable concentrically relatively to said hub, a plurality of sets of bearings on said rim for coöperation with each of said members, the bearings for each member being staggered and the bearings for one member facing circumferentially in one direction and those for the other member facing circumferentially in the opposite direction, and yielding means interposed between said members and operating to hold the same normally in a central position relatively to said rim.

2. A resilient wheel comprising a hub, a rim, and cushioning means interposed between said hub and rim and comprising a plurality of members rotatable concentrically relatively to said hub, a plurality of sets of bearings on said rim for coöperation with each of said members, the bearings for each member being staggered and the bearings for one member facing circumferentially in one direction and those for the other member facing circumferentially in the opposite direction, and a plurality of sets of shoes arranged on each member and engaging respectively with the plurality of sets of corresponding bearings on the rim, and yielding means interposed between said members and operating to hold the same normally in a central position relatively to said rim.

3. A resilient wheel comprising a hub, a rim, and cushioning means interposed between said hub and rim and comprising a plurality of members rotatable concentrically relatively to said hub, a plurality of sets of curved bearings arranged in annular rows on said rim and coöperating with each of said members, the bearings for one member facing circumferentially in one direction and the bearings for the other member facing circumferentially in the opposite direction, and yielding means interposed between said members.

4. A resilient wheel comprising a hub, a rim, and cushioning means interposed between said hub and rim and comprising a plurality of members rotatable concentrically relatively to said hub, a plurality of sets of curved bearings for coöperation with each member arranged in annular rows on said rim, the bearings for one member facing circumferentially in one direction and the bearings for the other member facing circumferentially in the opposite direction, a plurality of sets of shoes arranged on each member for coöperation with the corresponding bearings on the rim, and yielding means interposed between said members.

5. A resilient wheel comprising a hub, a rim, and cushioning means interposed be-

tween said hub and rim and comprising a plurality of members rotatable concentrically relatively to said hub, curved bearings arranged on said rim for coöperation with said members, the bearings for one member facing circumferentially in one direction and the bearings for the other member facing circumferentially in the opposite direction, shoes pivoted on each of said members and each shoe having a curved face engaging one of said curved bearings, and yielding means interposed between said members.

6. A resilient wheel comprising a hub, a rim, and cushioning means interposed between said hub and rim and comprising a plurality of members rotatable concentrically relatively to said hub, a plurality of sets of bearings for coöperation with each of said members, the bearings for one member facing circumferentially in one direction and the bearings for the other member facing circumferentially in the opposite direction, one of said members having a plurality of spring seats and a plurality of stops and the other member having a plurality of cushioning lugs each of which is adapted to engage one of said stops, and a plurality of springs each engaging one of its ends with one of said spring seats and its opposite end with one of said lugs.

7. A resilient wheel comprising a hub, a rim, and cushioning means interposed between said hub and rim and comprising a plurality of cushioning members rotatable concentrically relatively to said hub, a plurality of sets of bearings for coöperation with each of said members, the bearings for one member facing circumferentially in one direction and the bearings for the other member facing circumferentially in the opposite direction, one of said members having a plurality of spring seats and a plurality of stops and the other member having a plurality of cushioning lugs each of which is adapted to engage one of said stops, a driving member turning with said hub and provided with a plurality of driving lugs each of which is arranged between one of said spring seats and an adjacent cushioning lug, and a plurality of sets of springs, one member of one set being arranged between one side of each driving lug and the adjacent spring seat and one member of the other set being arranged between the opposite side of said driving lug and the adjacent cushioning lug.

8. A resilient wheel comprising a hub, a rim and cushioning means interposed between said hub and rim, comprising a plurality of cushioning members rotatable concentrically relatively to said hub, one of said members being provided with a plurality of annular sets of spring seats, a plurality of annular sets of stops, each stop being opposite one of said spring seats,

the other cushioning member being provided with a plurality of annular sets of cushioning lugs each of which engages with one of said stops, a driving member turning with 5 said hub and having a plurality of driving lugs each of which is arranged between one of said spring seats and an opposing stop, a set of springs interposed between the seats of one set of seats and the corresponding 10 cushioning lugs, another set of springs interposed between the seats of the other set of seats and one side of said driving lugs, another set of springs interposed between the other set of cushioning lugs and the opposite 15 side of said driving lugs, and said rim being provided with bearings for co-operation with said cushioning members, the bearings for one cushioning member facing circumferentially in one direction and the bearings for 20 the other cushioning member facing circumferentially in the opposite direction.

9. A resilient wheel comprising a hub member, a rim member, one member carrying a plurality of bearings, the other member 25 carrying concentrically a plurality of parts revoluble thereon, each of said parts being provided with an equal number of bearings for engagement in opposite circumferential directions with said first mentioned bearings, resilient means between 30 said revoluble parts to oppose their relative rotation in one direction and spring bases also carried by the member with which the revoluble parts are concentric which 35 bases intersect the said resilient elements.

10. In a resilient wheel, a rim, a hub centrally positioned therewith, and a resilient element to yieldingly resist all relative movements of said rim and hub radially and 40 also circumferentially in both directions, said resilient element being so placed as to be affected equally in a circumferential direction in all positions of rotation of the wheel.

45 11. In a resilient wheel, a rim, an axle centrally positioned therewith and a resilient element to yieldingly resist the relative movement of said rim and axle radially and also circumferentially in both directions, said resilient element being so placed as to be effected equally in all positions of the wheel and in combination another resilient element so placed as to resist the relative movement of said rim and axle radially 55 only.

12. In a resilient wheel, a hub member, a rim member, means for yieldingly maintaining said members in their normal relative positions, comprising revoluble parts carried by one of said members, means of engagement of said parts with said other member by circumferential contact in opposite directions, such means of engagement being arranged successively in staggered relation,

and resilient means to tend to maintain such 65 contact.

13. In a resilient wheel, a rim member, a hub member rotatable in relation thereto, and devices for yieldingly holding said members in their normal relation, which 70 devices include a resilient element compressible in a circumferential direction so placed as to cushion every circumferential stress between said members by like action in all positions of the rotation of the wheel. 75

14. In a resilient wheel, a driving member, a driven member movable radially and also circumferentially in both directions in relation thereto, a resilient element operating uniformly in all circumferential positions of said wheel to yieldingly resist all 80 of said movements, and means whereby all the forces of drive are transmitted from said driving member to said driven member directly through said resilient element. 85

15. In a wheel, a rim member, a hub member movable radially or circumferentially in either direction in relation to said rim member, a yieldable element, and means whereby said yieldable element is actuated to yield 90 circumferentially of said wheel in like manner in all positions of the rotation of the wheel by any relative radial or circumferential movements of said hub and rim members. 95

16. In a wheel, a hub, a rim, said hub and rim being movable radially and circumferentially in relation to each other, a resilient unit operatively associated therewith, and means whereby a relative radial movement 100 of said hub and rim is resisted by the tension of said resilient unit from end to end, while a relative circumferential movement of said hub and rim is resisted by the tension of said resilient unit only between an 105 end and a point intermediate its ends, the construction and arrangement being such that each of said movements influences said resilient unit uniformly in all rotary positions of the wheel. 110

17. In a resilient wheel, a hub member, a rim member movable radially or circumferentially in either direction with respect to said hub member, resilient means compressed in a circumferential direction to 115 yieldingly resist all of said relative movements of said hub and rim members whether said hub and rim members are concentric or eccentric, including a resilient element so positioned as to be equally affected in all 120 positions of rotation of said wheel by any of said movements.

18. A resilient wheel comprising a hub member, a rim member, one of said members being provided with a plurality of fixed 125 driving elements and also with coaxial revoluble parts which operatively engage the other of said members in substantially con-

centric position, and resilient means to yieldingly resist the rotation of said coaxial parts in opposite circumferential directions, said resilient means being intersected by said driving elements.

19. In a resilient wheel, a driving member, a driven member, a plurality of resilient elements to cushion said wheel

against the effect of shock, load or drive, each of said resilient elements being of 10 greater length in resisting the force of shock than in resisting the force of drive, the construction and arrangement being such that said resilient elements are unaffected by said driving member under load or shock. 15
